DESIGN FOR A LIFTER FOR A BROILER OR THE LIKE

Don Tichenor, Battle Creek, Mich., assignor to
Martin C. Friedman, Hollywood, Fla., and Irwin
M. Stone, Cleveland, Ohio

Application August 8, 1940, Serial No. 94,306

Term of patent 7 years

To all whom it may concern:

Be it known that I, Don Tichenor, a citizen of the United States and a resident of Battle Creek, in the county of Calhoun and State of Michigan, have invented a new, original, and ornamental Design for a Lifter for a Broiler or the like, of which the following is a specification, reference being had to the accompanying drawing, forming a part thereof.

In the drawing: Fig. 1 is a top plan view of a

lifter for a broiler or the like, showing my new design; Fig. 2 is a side elevational view thereof; Fig. 3 is an end elevational view thereof, looking toward the lifting end of the article; and Fig. 4 is an end elevational view thereof, looking toward the handle end of the article.

I claim:

The ornamental design for a lifter for a broiler or the like, as shown.

DON TICHENOR.
